FIG. 4

UNITED STATES PATENT OFFICE

2,535,491

STROKE SAW

Philip C. Felton, Norristown, Pa.

Application April 14, 1947, Serial No. 741,158

6 Claims. (Cl. 143—68)

1

This invention has general reference to motor-actuated saws or devices while it relates, more particularly, to the species or form thereof commonly known as stroke saws in which the blade has a substantially straight stroke as distinguished from an oscillatory or swinging movement.

The primary object of my invention is to provide an improved construction of portable stroke-saw, which can be economically built; that is comparatively light in weight; and which is exceptionally easy to manipulate for cutting rough-horuses useful in building operations, for the support of a series of steps, and so forth.

Another object of my invention is to provide a power-operated stroke-saw which makes a straight clean cut to the point desired and is easily retracted for a repeat of the operation from a different angle with resultant production of a sharply defined corner needing no subsequent trimming or squaring.

A further object of this invention is to provide a portable stroke-saw of the species above defined, in which the power unit is so located that it may serve as a fulcrum or pivot about which said unit is easily turned in either direction to effect undulate, or curvilinear cuts of any desirable radius by the simple expedient of using a different width of saw-blade.

A still further object of my invention is to provide a portable stroke-saw preferably usable for top surface work so that the weight thereof materially augments its efficiency.

While the foregoing definitions are indicative, in a general way, of the aims of my invention, other objects with ancillary advantages will be evident, or later on herein noted, to those skilled in the art upon a full understanding of the construction, arrangement and operation of the means hereinafter fully disclosed; while it will also be appreciated that my invention is susceptible of other embodiment or structurally modified forms coming equally within the terms and scope of the concluding claims.

In the drawings—

Fig. 1, Sheet 1, is a perspective view of a typical and portable stroke-saw constructed in accordance with my improvements.

Fig. 2, Sheet 2, is a top plan view of the portable stroke-saw.

Fig. 3 is an end elevation of the same, as viewed looking from the left towards the right-hand side thereof.

Fig. 4, Sheet 3, is a side elevation of the portable stroke-saw as viewed looking at the right-hand side thereof.

2

Fig. 5, Sheet 2, is a broken sectional elevation taken on the plane designated by the angled arrows V—V, in Fig. 4, and drawn to a larger scale for clearer illustration of structural details.

Fig. 6, Sheet 1, is a plan section, taken as indicated by the angled arrows VI—VI in Fig. 4, also drawn to the same scale as Fig. 5 and for like reasons.

Fig. 7, Sheet 3, is a local section on the plane VII—VII in Fig. 4.

Fig. 8, Sheet 3, is a similar section on the plane VIII—VIII of Fig. 4.

Fig. 9, Sheet 3, is a fragmentary sectional elevation taken approximately as indicated by the angled arrows IX—IX to the left hand of Fig. 5; and

Fig. 10, Sheet 1, is a perspective view of a guide element hereinafter fully explained.

In describing the form of my invention exemplified by the accompanying three sheets of illustrative drawings, specific terms will be employed for the sake of clarity, but it is to be understood the scope of said invention is not thereby limited, each such term being intended to embrace all equivalents which perform the same function for an analogous purpose.

Referring more particularly to the drawings the reference character 11 designates a rectangular base or platform conveniently, although not essentially, of hard wood, to the under side of which are rigidly attached side and an intermediate runner or skids 12, 12, and 13 respectively, likewise made of wood with the grain lengthwise and having the ends rounded at 14. These skids 12, 12 and 13 are preferably protected on their active faces with wear-resistant metal strip 15 secured thereto in any suitable manner; while it is to be remarked that the platform 11, is provided with a rectangular cut-out 16 at one side, intermediate the ends thereof, for reasons later on herein made clear.

Projecting upwardly from, and rigidly attached to, the platform 11 is an upright member 17, also of wood, the same being further rigidified by metal braces 18, 19 appropriately held in place by wood-screws 20, and respectively connecting from the said member 17 to the platform 11 and the right-hand side skid 12, as clearly shown in Figs. 1-3, more particularly. The upright member 17, it is to be remarked, is of special formation to embody a forward or main section 21 with a rearwardly-extending or approximately horizontal hand-grasp 22, whereas the front edge includes a lower vertical part 23 and an upper rearwardly inclined part 24. On the other hand, the rear edge of the member 17 includes a forwardly

inclined part 25 and an upper rearwardly inclined part 26. On the other hand, the rear edge of the member 17 includes a forwardly

inclined upper part 25 above the hand-grasp 22, and a concave curvature 26 merging from said grasp to the rear edge of the platform 11. In addition to the metal braces 18, 19, the upright member 17 is, preferably, fitted with an inverted L-shape reinforcement 27 of wood, conveniently at the left-hand forward side, in order to provide adequate support for a metal bearing block 28 appropriately secured in place by a bolt 29 and a lag screw 30, for example, with associated washers 31.

Journalized in the bearing block 28 is a shaft 32 the relatively projecting reduced portions 33, of which are screw-threaded for application of lock-nuts 35 and clamp-washers 36, whereby a single, or multi-grooved drive-pulley 37 is securely fixed to the portion 33, and a fly-wheel 38 correspondingly mounted on the portion 34 with a spacer collar 39, made fast by a set-screw 40 intermediate the wheel 38 and the bearing 28. It is to be remarked that both the grooved pulley 37 and the fly wheel 38 may be made of wood, for a reason hereinafter set forth.

The multi-grooved pulley 37 is conveniently co-ordinated, as by one or more round section leather belts 41, to a similarly-grooved small pulley 42 fast on the outer end of the drive-shaft 43, of a motor 44, connected from any conveniently located outlet or source of electric current supply—not shown—by a conductor 45 to a snap switch 46 whereby the current is turned “on” and “off,” such switch 46 being conveniently located, as shown, for easy manipulation by the fingers of the operator of the stroke-saw, as readily understood by those conversant with the art.

The motor 44, is suitably mounted on a wood or other material base 47 which, in turn, is seated on the forward portion of the platform 11 and rigidly secured thereto by aid of hold-down bolts 48 with lock washers 49; while provision is made for accurate adjustment of said motor with its pulley 42 to properly align in respect to the drive-pulley 37, by aid of passing bolts 48 through suitable slots 50, Figs. 1 and 4, formed for the purpose in the parts 11 and 47.

Appropriately rabbeted at 51, see Figs. 7 and 8, into the upright member 17 is an angularly related post 52 having upper and lower relatively stepped portions or metal spacers 53, inwardly of the ends of said post, as indicated at 54 in Fig. 1; said spacers being rigidly held in place by countersink headed through bolts 55 and an intermediate bolt 55' engaged through the parts 52, 17 only as best understandable from an examination of Fig. 5, more particularly. Attached to the face 54 of the spacers 53 with capacity for lateral adjustment, as later on herein pointed out, are a pair of vertically directed guide elements 56, said elements 56 being held in position by aid of screw-bolts 57 threadedly engaging holes 58 in the elements 56 with free passage through larger diameter holes 59 in the spacers 53, and beyond which they are equipped with clamp-washers and lock-nuts 60; it being understood the post 52 is regionally notched out at 61 to accommodate the parts 60 and to enable release or tightening-up of the latter, in an obvious manner.

Reciprocatively-engaged, by opposed grooves 62, Fig. 8, intermediate the confronting edge portions of the guide-elements 56 is a slide 63 having a fulcrum-stud 64 threaded therein and, to the outer portion 65 whereof is pivotally connected, by aid of a metal bushing 66 with associated washers 67 and a cotter pin 68, the lower end of a wood bar or pitman 69, in turn similarly pivoted,

by corresponding means 65'—68', to the fly-wheel 38 in eccentric relation to the axis of rotation of the latter. At this juncture it is noteworthy that the respective ends of the pitman 69 are longitudinally-cut inwards at 70 and fitted with clamp-means 71 to restrain the bushings 66 against displacement; while it is further observable that the fly-wheel 38 is, preferably equipped with a metal counterbalance 72.

A conventional type saw-blade 73 having the forked end 74 divergently tapered at 75 for abutment against the flange 76 of the proximately related fulcrum-stud 64; while said blade 73 is secured in place by a screw-stud and lock washer 77; the former 64 of which is threadedly engaged in the slide 63 at 78, Fig. 5. In addition the saw-blade 73 is further constrained to direct stroke-action by means of a guide element or plate 79 having a slot 80 through which the back portion of said blade is reciprocated; while said plate is conveniently secured to the lower end of the post 52, as by screws 81, in an obvious manner, see Figs. 1, 5 and 6. A steadyng handle 82 is conveniently secured to the left-hand side of the upright member 17; while 83 is a carrying-handle for the device, said handle 83 being preferably secured by screws 84 to the inclined edge of the member 17. Attention is also directed to the fact that the ends of the respective guide elements 56 are preferably provided with suitable means, conveniently in the form of small diameter through-bolts 85 having lock-nuts 86, whereby said elements 56 can be accurately adjusted and maintained in coactive operating engagement with the slide 63, as readily understood by those conversant with the art.

From the foregoing it is thought the merits and advantages of this invention will be readily apparent, while it is obvious that by making most of the parts from hard-wood with metal being used only, where necessary, that I have provided a portable and comparatively light-weight stroke-saw that is just as serviceable in the field, or at a building operation, as it is in the shop. As a matter of fact, when constructed as described, the device complete with a quarter horse-power electric motor does not exceed thirty-five pounds in weight.

In use, the operator simply marks out the cutting work desired on the rough or finished lumber, places the saw in position thereon for starting the cut, grasps the steadyng-handle 82 in one hand, snaps the switch 46 to the “on” position and then guides the blade 73 by taking hold of the grasp 22 with the other hand, and pushes the device as a unit with the blade 73, reciprocating vertically, along the plotted line or lines in an obvious manner. It is to be also particularly noted that by positioning the saw-blade 73 as shown and described it positively operates with a straight stroke, free from vibratory deflection while the guard-plate 79 effectively obviates the accumulation of saw-dust about the blade 73 and thereby effectively prevents the “kerf” cut by said blade from getting choked up with dust. It is still further noteworthy that by my invention I provide a portable stroke-saw which can be economically built, that will be found to be a great money and time saver in the wood working and building trades inasmuch as, heretofore, the preparation and cutting of rough “horses” and other kindred lumber pieces has invariably necessitated the service of two or more men, whereas my device is easily and efficiently operable by one man. Again my device further

eliminates the need for the use of expensive band or skill-saws, as well as the dangers incidental to their usage, in the preparation of rough "horses" and so forth in building operations; while the unit can be used at the scene of an operation and thus avoid truckage costs, as well as expensive mill-work. Still further it is apparent my improved stroke-saw is equally usable for "truing" the rough ends of flooring boards, studding, joists, rafters, and so forth at the 10 operation.

Finally it will be readily appreciated from the foregoing disclosure that by my invention I have provided a device in which the several objects recited are achieved, and which is well adapted to fully meet the conditions of practical use. Accordingly, as various other possible embodiments of my invention may be made and structural changes adopted, such for instance as the substitution of light metal for hard-wood, it is to be understood that all matters hereinbefore set forth and shown by the accompanying drawings are to be construed as exemplary and not as limitative.

Having thus described my invention, I claim:

1. In a portable stroke-saw the combination of a platform with spaced runners or skids thereunder and an opening in one side thereof, a motor secured on the forward portion of the platform in advance of the side opening, and said motor being of a size or weight effective to serve as a fulcrum or pivot about which the stroke-saw is turnable in either direction; an upright member lengthwise of the platform including a rearwardly extending manipulator hand-grasp and a laterally projecting steadyng handle at one side thereof; brace elements rigidly securing the upright member to the platform and supports; means at one side of the upright member affording reciprocatory attachment for a saw blade, and a guide element at the lower end of said member for the back portion of the blade; means at the other side of the upright member jointly affording, with the top of said member, firm mounting for a stationary bearing; a shaft journaled in the bearing with a drive-pulley at one end and a fly-wheel at the other end; connector means coupling the fly wheel to the saw-blade reciprocatory attachment; and means operatively coordinating the drive-pulley to the output shaft of the power motor.

2. The invention of claim 1 wherein the upright member is formed to embody a forward main section and a rearwardly-extending hand-grasp; wherein the front edge of said member includes a lower vertical portion with an upper rearwardly-inclined part; wherein the rear edge

of the member aforesaid includes a forwardly-inclined edge above the hand-grasp with a concave curvature below the latter merging to the rear edge of the platform; and wherein the upright member further includes an inverted L-shaped side reinforcement and an opposing angular rabbeted post portion.

3. The invention of claim 1 wherein the drive-pulley is in the form of a multi-grooved disc; and wherein the fly-wheel is in the form of a disc having an inset counter balance.

4. The invention of claim 1 wherein the means connecting the fly-wheel to the means affording reciprocatory attachment for the saw-blade is in the form of a pitman; wherein each end of said pitman includes a bushing; and wherein laterally adjustable clamp means are fitted across the pitman ends to prevent displacement of the bushings.

5. The invention of claim 1 wherein the means affording reciprocatory attachment for the saw-blade comprises a slide embodying parallel grooves; wherein stationary spaced guide elements engage in the slide parallel grooves; and wherein adjustor means are provided across the ends of said guides.

6. The invention of claim 1 wherein the guide element for the back portion of the saw-blade includes an open-ended slot; and wherein said element is secured to the lower end of the upright member blade adjoining reciprocatory-attachment supporting means.

PHILIP C. FELTON.
